(57) **CLAIM**

The ornamental design for a pull-out drawer apparatus, as shown and described.

DESCRIPTION

FIG. 1 is a front perspective view of the design; FIG. 2 is a front elevational view of the design; FIG. 3 is a rear elevational view of the design; FIG. 4 is a first side elevational view of the design, with the opposite second side being a mirror image of the first side; FIG. 5 is a top plan view of the design; FIG. 6 is a bottom plan view of the design; and, FIG. 7 is a side elevational view of the design with the drawers in different degrees of extension out from the enclosure. The broken line showing is for illustrative purposes only, and forms no part of the claimed design.
